SONANT RESPIRATION INDICATOR

Morris W. Kleit, Teaneck, N. J.

Application March 18, 1943, Serial No. 479,670

7 Claims. (Cl. 128—207)

This invention relates to indicators for the respiration of patients who are under the influence of general anaesthetics, and has particular reference to such indicators applicable to patients breathing through the nose.

The problem to which this invention is addressed is well illustrated by the technique of dentists in the administration of nitrous oxide. The latter is inhaled by the patient through the nose, while his mouth is open so that the dentist may perform whatever dental work may be necessary. It is well known that patients react differently, sometimes in the most unexpected ways, to the gas. Frequently the patient's pulse and respiration becomes rather weak, and sometimes stop altogether; hence the patient may be regarded as in continuous danger. There is usually no history of the patient's action under the influence of gas, and if there were, the patient's reaction may be different. While the dentist is busy working in the mouth and using both hands in manipulating various instruments, he is unable to take the patient's pulse. Nor have the majority of dentists assistants or nurses to observe the patient. Yet a delay of a minute in changing the ratio of oxygen to nitrous oxide, or in completely shutting off the anaesthetic may result in a serious condition or even death of the patient.

One object of the invention, therefore, is to provide an improved device, including a sonant respiration indicator which shall give the operator a continuous indication of the condition of the patient without requiring visual reading or use of one or both hands.

Another object of the invention is the provision of an indicator which shall produce a sound, and which, without any manipulation by the dentist, shall instantly indicate the strength or weakness of the patient's respiration or the total cessation of breathing.

Another object of the invention is to furnish improved means such that the indicator shall sound only upon exhalation and be cut off on inhalation to prevent aspiration of air which would affect the carefully adjusted gas to oxygen ratio in degrees which may vary as the strength of the respiration diminishes.

Another object of the invention is to provide an improved device whereby the sonant indicator does not prevent the making of various adjustments, for instance at the exhalation nose piece, so that the device may be readily set to the needs of the individual patient.

In general, the invention has the further object of providing a sonant respiration indicator

so arranged and constructed in an improved manner as to be responsive to the relatively slight exhalation pressure of an unconscious patient whose mouth is held open, the indicator being simple, compact, durable, highly reliable in use, and light in weight.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Figure 1 is a diagrammatic view, with parts in elevation and other parts in perspective, showing a device embodying the invention, as applied to a patient of whom a fragmentary view is given in dotted lines.

Fig. 2 is an enlarged view of a device according to the invention with parts in section and parts in elevation.

Fig. 3 is an enlarged top plan view of the sounding member in detached position.

Fig. 4 is a view in elevation thereof.

Fig. 5 is a central sectional view, with parts in elevation showing the combined valve means and sounding member of the nose piece, according to the invention.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Referring in detail to the drawing, 10 denotes a device embodying the invention and illustrating a typical use thereof. The same may include any desired source 11 of a suitable anaesthetic, comprising a tank of nitrous oxide 12 and a tank of oxygen 13. The outlets of these tanks may be controlled as by pressure reducing and regulating devices 14, each of which includes a valve 15. From these devices 14 may extend sections of hose, such as tubes 16 which lead to a common fitting or mixing chamber 17, whence extends a

single flexible tube 18. The latter may lead into a branch fitting 19, from which extend flexible tubes 20 that connect into a nose piece device 21. Also connected to the tube 18 is an inflatable bag 22 of limp material which is used as a pressure indicator, the pressure being adjusted by a valve 23 of the chamber 17. It will be perceived that the proportions of nitrous oxide and oxygen may be adjusted at valves 15, and that these gases are continuously mixed together on their way to the nose piece, with the pressure of the mixture controlled and indicated. In general, when once the proportions and pressure of the mixture have been adjusted they need not be changed, except as may be required by a change in the condition of the patient indicated by the respiration, as hereinafter described. It will be appreciated that the structure thus far described is conventional and merely illustrative.

The sonant respiration indicator 21 may include a nose piece 24 made of any flexible material such as rubber, and being suitably shaped as desired to embrace the nose or at least the nostril portion. Preferably the nose piece 24 is formed with a continuous marginal inturned lip 25 of soft rubber to aid in forming a gas tight seal with the face of the patient. The lower end of the nose piece has sufficient depth to receive the nose and to contact the face immediately below the nose, as indicated by the patient shown in dotted lines. Opposite outlet ports 26 are provided at which the tubes 20 are connected to the nose piece to assist in holding the latter in position, the tubes 20 being turned around the sides of the head to the back of the head or neck, at which the fitting 19 is located. Connected to the nose piece 24 is a device 27 embodying the invention. The same may comprise a combined control and sonant indicator. For example, it may include a member 28 connected in a gas tight manner to the nose piece by any desired means schematically shown at 29. The member 28 may be of cylindrical or other required form, being a tube having a large inlet 30. It has a single, central outlet port 31 which is so small as to be capable of acting as a control to permit very little air to enter the nose piece during inhalation, so as not to unduly affect the ratio of anaesthetic to oxygen. Moreover, the smallness of this opening 31 permits it to serve as a sounding orifice in response to exhalations, even if the exhalation be very weak as in the case of an unconscious person. In general an opening of about 0.625 inches in diameter is satisfactory. This opening has rather sharp edges so as to constitute what is known in pneumatics as a thin edge orifice. Accordingly it has a high coefficient of friction and a low coefficient of discharge, whereby the rate of flow is reduced. This construction of the orifice 31 also enables the member 28 to serve as a sounding device. The action of the orifice 31 may be enhanced by inwardly concaving the end wall 32 in which the orifice is formed.

If the supply of nitrous oxide and oxygen mixture is sufficient a slight pressure may prevail in the tubes leading to the nose piece, this pressure dropping almost to zero during inhalation, so that the tendency for any flow through the orifice to the atmosphere 31 may be practically nil. During exhalation, the slight pressure in the tubes may be counteracted in part by the exhalation pressure, so that only a negligible quantity of gas may escape into the atmosphere. In fact some of the exhalation may return to the bag 22

so that any gas which has not been absorbed by the patient may again be used.

It is a natural physiologic action for a person to be capable of breathing through the nose while his mouth is open. When gas is first administered, the mouth may be closed, but is opened before the patient lapses into unconsciousness. As soon as the patient becomes unconscious, a wad of cotton is stuffed into the back of the mouth before the dentist begins to work on teeth. This cotton serves to prevent articles from accidentally falling into the patient's throat and reduces any tendency to breathe through the mouth, if it does not wholly prevent it. If the cotton should slip into the throat it may cut off the breathing through the nose, but this would be instantly indicated by the sounding device.

The best results are obtained by embodying in the device 27 a valve means for automatically cutting off the sounding device during inhalation. Thus air is avoided which might be inhaled and affect the delicate balance of the gas and oxygen mixture, especially when the patient's breathing becomes progressively weaker. In Fig. 5 is shown a device 27a comprising a sounding member 28a which is generally like that at 28, and any valve means 33. The latter may include a cylindrical casing 34 having in the lower part thereof a slideable cylindrical element 35. The elements 34, 35 may be threaded interconnected at 36. The lower part of element 35 may be thickened to provide a circular seat for a disc valve 37, which communicates with a clamping nipple 38 or other inlet. A helical expansion coil spring 39 bears on the top wall of element 34 and on the disc valve to hold the latter down on its seat. A pin 41 extends axially through the wall 40 and through the top wall 42 of the element 34, being upwardly urged by an expansion coil spring 43 extending around the pin and bearing on the wall 40 and on a collar 44 of the pin, which collar rests on the wall 42. For communication with the valve, the walls 40 and 42 may each respectively have a plurality of openings 45, 46. The member 28a may be removably sleeved on the casing element 34 with a snug fit.

In operation, the casing element is fixed, being secured to the nose piece 24 by the clamping nipple 38. By turning the casing element 34, the thread 36 causes the same to move and carry the pin 41 toward the valve 37 to limit the opening movement of the latter. The valve is normally closed by the spring 39 which is so weak as to permit the valve to open in response to exhalation pressure, in which case the valve is guided by the side wall of the casing element 35. The spring 43 is stronger than that at 39, and if the operator desires, he may manually press down on the upper projecting end portion of the pin and cause it to forcibly close the valve 37. Due to frictional contact between the sounding member 28a and the casing 34, the latter may be turned by turning the member 28a.

It will be noted that the sounding orifice is much smaller than the area of the ports 46 or of the ports 45, and that there is a substantial distance between the orifice 31 and the ports 46. Such spacing is important, because if too close, the turbulence caused at the ports 46 affects the orifice 31 so that no sound is produced. In general that spacing should be about one half of an inch. Some adjustment of the volume of sound is possible by axially sliding the member 28a to a desired position on the casing 34. The sonant indication is so sensitive as to vary in volume with

the volume of respiration, thus giving the dentist a warning signal when it becomes very weak.

The invention thus relieves the dentist of the loss of time in attempting to check the patient from time to time, and reduces the nervous strain due to the uncertainty of the patient's condition from moment to moment, and is simple, practical, convenient and reliable in use.

It is interesting to note that my device is adapted to indicate the volume, frequency and depth of respiration, with the mouth open or closed, enabling the dental or medical anaesthetist to check the condition of the patient whose mouth is initially closed and is opened after lapse into unconsciousness. The changes in volume, frequency and depth of respiration, indicated by the sounding device, are particularly instructive to the ear of the skilled anaesthetist with reference to the first, second, third and fourth stages of anaesthesia. The device produces a whistling sound by the exhalation pressure acting against the edge of the opening. So sensitive is my device to those skilled in its use that the presence of an anatomical obstruction, such as a deviated septum, a tumor, or adenoids will be indicated, so that the action of the anaesthetist may be governed accordingly. Pressure on the nerves causing interference with respiration will be indicated or suggested. Accidental loosening of the nose piece, or shifting of a cotton wad in the back of the mouth to partially obstruct the respiratory tract, as where the dentist presses down on the tongue, will readily show up. Where gas is used for analgesia to dull the pain of the conscious patient, the tendency to breathing through the mouth may be overcome by instructing the patient to listen to the sounding device to thus make sure that he is breathing through the nose.

I claim:

1. A sonant respiration indicator whereby a dentist can continuously check the condition of a patient who is under the influence of a gaseous anaesthetic, including a member arranged and constructed to embrace the nostril portion of a patient who is breathing through the nose, said member being adapted to communicate with a means for adjustably supplying oxygen and an anaesthetic gas to the member to be inhaled by the patient, said member having an exhalation outlet, and a sounding device external of the member and being connected thereto in communication with the exhalation outlet, the sounding device having an outlet so substantially small that the exhalation gases are capable of producing a sound whose volume varies with the breathing of the conscious and unconscious patient, said means being so adjusted as to be incapable of causing operation of the sounding device during inhalation.

2. A sonant respiration indicator whereby a dentist is given timely warning of the condition of a patient under the influence of nitrous oxide, including a nose piece having a casing adapted to snugly embrace only the nose of the patient, the casing having an inlet opening, a tube connected to the casing at said inlet for supplying gaseous anaesthetic thereto, said casing having an outlet opening and a sounding device connected to the casing at said outlet, a closure valve for the outlet openable in response to exhalation pressure, the sounding device having a sound orifice substantially smaller in area than said tube and said openings, and being normally in continuous communication with said outlet subject to the

control of the valve, whereby a weak exhalation is capable of operating the sounding device.

3. A sonant respiration indicator for a dental patient breathing gaseous anaesthetic through the nose including a nose piece having a casing, a sounding device connected to the casing, a tube connected with the nose piece and providing with the latter a passage of relatively large area for communicating only exhalation pressure to the sounding device, the latter having a sonant orifice of substantially smaller area, the orifice having a thin sounding edge, and the casing having a relatively large volume with the sounding orifice being sufficiently spaced from the nose piece to prevent turbulence of gases therein from preventing operation of the sounding orifice, whereby the sounding device is responsive to the weak exhalation of the unconscious patient.

4. A sonant respiration indicator including a nose piece having means for embracing the nose and having an inlet portion, a tube connected to the nose piece at the inlet portion, means for controlling the supply of a gaseous anaesthetic thereto to be inhaled by the wearer, the nose piece having an outlet portion, a valve means carried by the nose piece that automatically closes the outlet to prevent flow of gases into the casing through the outlet upon inhalation and permits free flow of gases from the outlet upon exhalation, and a sounding device having a casing connected to said nose piece to communicate with the valve means, the sounding device having a thin edge orifice, the latter being sufficiently small to render the sounding device operative by an exhalation through the nose and the casing being of sufficient size with the orifice being at a sufficient distance from the valve means to prevent turbulence of gases caused by the latter from affecting the operation of the sounding device.

5. A sonant respiration indicator including means for supplying to a patient a mixture of oxygen and anaesthetic gas, at an adjusted pressure, including means communicating solely with the nose while the mouth of the patient is open, valve means responsive to gaseous pressure for communicating with the nose to permit exhalation into the atmosphere at an adjusted pressure and to automatically cut off communication with the atmosphere during inhalation, and a sounding device communicating with the valve means for the discharge of the exhalation into the atmosphere, the sounding device being normally continuously operative upon each exhalation and being constructed to be so sufficiently sensitive to be responsive to relatively weak exhalations of the unconscious patient with the volume of sound varying to thus indicate the condition of the patient under the influence of said anaesthetic.

6. A sonant respiration indicator including a nose piece arranged and constructed to fit solely over the nose of the patient, said nose piece having a first port adapted to continuously communicate with a source of gaseous anaesthetic, and a second port communicating with the atmosphere, the nose piece having a chamber for the nostrils having direct, unrestricted continuous communication with the first port, and with the second port during exhalation, a valve means for the second port normally closing the same during inhalation and being responsive to exhalation pressure to open the second port, a sounding device communicating with said chamber through the second portion when the valve means is open, the sounding device having means so constructed and

arranged that the exhalation pressure of an unconscious person is capable of causing operation of the sounding device, means for mounting the sounding device so that the same is adapted for continuous cooperation with the chamber, and means for so controlling the supply of anaesthetic gases to the chamber that the same are so relatively completely inhaled by the patient as to avoid pressure in the chamber sufficient to open the valve means during inhalation.

7. An sonant respiration indicator including a nose piece having means for embracing the nose, and having an outlet portion, a tube connected to the nose piece at the outlet portion, means for controlling the supply of a gaseous anaesthetic thereto to be inhaled by the patient, the nose piece having an outlet portion, a valve means carried by the nose piece that automatically closes the outlet portion upon inhalation and permits a free flow of gases from the outlet portion upon exhalation, and a sounding device having a casing

connected to the nose piece to communicate with the valve means, the sounding device having a thin edge orifice, the latter being sufficiently small to render the sounding device operative by an exhalation through the nose, and the casing being of sufficient size with the orifice being at a sufficient distance from the valve means to prevent turbulence of gases caused by the latter from affecting the operation of the sounding device, the control means being set so that the pressure of the gaseous anaesthetic is insufficient to operate the sounding device during inhalation, the valve means including a movable casing, a valve, and a spring for the latter, said valve means having means forming a part of the casing for adjusting the flow through the valve means by movement of the casing thereof, and the casing of the sounding device being connected to the casing of the valve means for use as a finger piece for adjusting the valve means.

MORRIS W. KLEIT.
